US00D759423S

(12) **United States Design Patent**
Gamble et al.

(10) **Patent No.:** **US D759,423 S**
(45) **Date of Patent:** **** Jun. 21, 2016**

(54) **FOOD WASTE DISPOSER**

(71) Applicant: **Emerson Electric Co.**, St. Louis, MO (US)

(72) Inventors: **Kelly T. Gamble**, Waterford, WI (US); **Deborah R. Groshek**, Kenosha, WI (US); **Eric J. Schultz**, Thiensville, WI (US); **Randall E. Hammer**, Muskego, WI (US); **Grey B. Parker**, West Bloomfield, MI (US); **Josiah J. Lacolla**, Madison Heights, MI (US)

(73) Assignee: **Emerson Electric Co.**, St. Louis, MO (US)

(**) Term: **14 Years**

(21) Appl. No.: **29/514,363**

(22) Filed: **Jan. 12, 2015**

(51) LOC (10) Cl. **31-00**

(52) U.S. Cl.

USPC **D7/375**

(57) **CLAIM**

The ornamental design for a food waste disposer, as shown and described.

DESCRIPTION

FIG. 1 is a perspective view of a food waste disposer embodying our new design;

FIG. 2 is a front elevational view of the food waste disposer of FIG. 1;

FIG. 3 is a rear elevational view of the food waste disposer of FIG. 1;

FIG. 4 is a top plan view of the food waste disposer of FIG. 1;

FIG. 5 is a bottom plan view of the food waste disposer of FIG. 1;

FIG. 6 is a left elevational view of the food waste disposer of FIG. 1; and,

FIG. 7 is a right elevational view of the food waste disposer of FIG. 1.

The broken lines in all views are for the purpose of illustration and are not part of the claimed design.

1 Claim, 5 Drawing Sheets
